UNITED STATES PATENT OFFICE.

WILLIAM A. E. HENRICI, OF BOSTON, MASSACHUSETTS, ASSIGNOR, BY MESNE ASSIGNMENTS, TO LIBERTY TRUST COMPANY, OF BOSTON, MASSACHUSETTS, A CORPORATION OF MASSACHUSETTS, TRUSTEE.

REVERSING MECHANISM.

1,107,943.

Specification of Letters Patent. Patented Aug. 18, 1914.

Application filed January 28, 1907. Serial No. 354,356.

To all whom it may concern:

Be it known that I, WILLIAM A. E. HENRICI, a citizen of the United States, residing at Boston, county of Suffolk, and State of Massachusetts, have invented an Improvement in Reversing Mechanism, of which the following description, in connection with the accompanying drawing, is a specification, like letters on the drawing representing like parts.

This invention relates to reversing mechanism, and has for its object to provide a novel reversing mechanism by which the direction of movement of a driven member may be quickly and instantly reversed at any desired predetermined times.

The invention comprises a reversing mechanism and a controller therefor which is arranged to control the time of the reversing action, and this controller is preferably actuated by a time mechanism which can be adjusted so as to render the controller active to cause a reversal of the movement at different stated periods of time.

One embodiment of my invention is shown in the drawings and will first be described, and then the novel features of the invention will be pointed out in the appended claims.

In the drawings, Figure 1 is a section on line $x-x$, Fig. 2; Fig. 2 is a horizontal section on substantially the line $y-y$, Fig. 1; Fig. 3 is a section on the line $a-a$, Fig. 2; Fig. 4 is a sectional view on line $b-b$, Fig. 5 showing the brake; Fig. 5 is a detail of the brake; Fig. 6 is a section on line $c-c$, Fig. 3; Figs. 7, 8 and 9 are detail views showing the action of reversing the clutches; Figs. 10 and 11 are details showing the controller in different positions; Figs. 12 and 13 are details showing the lock for the controller; Fig. 14 is a section on substantially the line $f-f$, Fig. 1; Fig. 15 is a view looking to the right taken on substantially the line $g-g$, Fig. 3; Fig. 16 is a top plan view partly broken out of the parts shown in Fig. 15; Fig. 17 is a section substantially on the line $h-h$, Fig. 1; Figs. 18 and 19 are details of the brake-controlling device; Fig. 20 is an enlarged section on line $i-i$, Fig. 15; Fig. 21 is an enlarged section on line $k-k$, Fig. 15; Figs. 22 and 23 are details

of the time mechanism for reversing the clutches.

My improved reversing mechanism is adapted to be used with a great variety of machines where it is necessary to reverse the direction of motion of a driven element at stated periods of time.

I have herein shown my invention as interposed between a rotary driving shaft and a rotary driven element, although it will be understood that the nature of the driven element, whether a rotary or a reciprocating element, does not affect in any way the invention. In the present embodiment of my invention also the power is transmitted from the driving member to the driven member by means of friction clutches, although this is not essential to the invention and other forms of clutches might be used without departing therefrom.

The driving member is herein shown as a shaft 3 which may be driven in any suitable way, as by means of a driving pulley 4 and the driven element is shown as a gear 5 mounted on a suitable shaft 6. This gear is illustrated as a worm-gear and is driven by a worm 7 carried by a driven shaft 8. The particular form of driven member and manner of gearing it to the driven shaft 8 is not essential, however.

Referring now to Fig. 6 in which the arrangement of the clutch mechanism for connecting the two shafts 3 and 8 is illustrated, it will be observed that the shaft 3 has fast thereon a sprocket-wheel 9 over which runs a sprocket-chain 10 that connects said wheel 9 to another sprocket-wheel 11 loose on the shaft 8. Loose on the shaft 3 is a gear-wheel 12 which meshes with a gear 13 fast on the shaft 8. The sprocket-wheel 9 and the gear-wheel 12 are adapted to be connected by a suitable clutch 14, and similarly the gear-wheel 13 which is fast on the shaft 8 and the sprocket-wheel 11 which is loose thereon are adapted to be connected by a suitable clutch 15. The clutches 14 and 15 may be of any suitable construction, but I prefer for many reasons to employ the clutch shown in Patent No. 840,847, dated January 8, 1907, and this is the type of clutch illustrated in the present drawing. This clutch is a friction clutch in which one clutch member is in the

form of a friction coil, and the other in the form of a friction drum which is encircled by the coil. The two clutches 14 and 15 are alike in every respect and each comprises a 5 friction drum 16 about which is coiled a friction coil 18. Each friction coil has its ends fast to two collars 21 loosely mounted on the corresponding drum 16, and is inclosed by a housing 19. The housing 19 of 10 the clutch 14 is fast to the shaft 3 and it has a hub 20 to which the sprocket-wheel 9 is fast, and the drum 16 of said clutch is loose on the shaft 3. The housing of the clutch 15 is loose on the shaft 8 and has a 15 hub 20 to which the sprocket-wheel 11 is fast, while the drum 16 of said clutch is fast to said shaft 8 and has fast thereto the gear 13.

Each clutch is thrown into operation by 20 turning the collars 21 thereof in opposite directions, thereby to tighten the coil 18 about the drum. This turning of the collars in opposite directions is accomplished by means of a clutch actuator 22 which is fast 25 to a clutch-sleeve 23 mounted on the shell 19 for longitudinal movement. Each clutch-sleeve is shown as having a groove 24 therein to receive a fork by which the clutch-sleeve is shifted longitudinally. To 30 avoid confusion, however, I have designated the fork of the clutch 14 by the reference numeral 25, and that of the clutch 15 by the reference numeral 26.

Suffice it to say that when either of the 35 clutch-sleeves 23 and the connected actuator 22 are moved to the left Fig. 6, the corresponding clutch is thrown into operation and when they are moved to the right, the clutch is released. As the parts are shown 40 in Fig. 6, therefore, the clutch 14 is in operation, and the clutch 15 is loose or is inactive, and the gear 12 is therefore clutched to the driving shaft 3, while the gear 13 is loose from the sprocket-wheel 11. The rotation 45 of the driving member 3 is communicated through the clutch 14 to the gear 12, and said gear 12 rotates the gear 13 which is fast to the shaft 8, the rotation of said shaft being permitted because the 50 clutch 15 is inactive.

With the arrangement shown in Fig. 6, therefore, the driving shaft 3 drives the driven shaft 8 through the clutch 14, and the two shafts rotate in opposite directions. If 55 the clutch 14 is released or rendered inactive and the clutch 15 is clutched or thrown into operation, then the sprocket-wheel 11 and the gear 13 will be clutched together by said clutch 15, and the shaft 8 will be driven 60 from the shaft 3 through the sprocket-wheels 9, 11 and the clutch 15, and said shaft 8 will be driven in the same direction as the shaft 3.

The mechanism for shifting the clutches 65 herein illustrated comprises a suitable actuator

which is adapted to be brought into engagement with the forks of either or both clutches at the proper time to shift said forks and consequently the sleeves 23 in the proper direction.

The forks 25 and 26 are mounted on rods or guides 27 and 28, and are provided with projections or noses 29 and 30, respectively, see Figs. 8 and 9. Situated between the noses are two sliding actuators 31 and 32, 70 see Fig. 1, and these actuators have associated with them sliding bolts 33 and 34, respectively, said bolts being mounted for movement transversely of the slides. The bolts normally stand within the limits of 80 the sliding actuators, but they may be thrown out transversely thereof in one direction or the other into position so that the ends thereof will engage the noses 29 and 30 to shift the clutches as the actuators are reciprocated. The bolt 34 acts to throw the clutches into operation and for convenience I will refer to it as a "knock-in" bolt. The bolt 33 acts to throw the clutches out of operation and for convenience I will refer to 90 it as a "knock-out" bolt.

Referring now to Figs. 8 and 9, the full lines show the position of the forks 25 and 26, and their projections 29 and 30 when the parts are in the position shown in Fig. 95 6, and in this figure the bolts 34 and 33 are thrown out in opposite directions so that the projections 29 and 30 stand in the path of movement of said bolts as the actuators 31 and 32 are reciprocated. When the bolts 100 are thus thrown out, as shown in Fig. 8, it will be seen that the movement of the actuators to the right will shift the fork 25 into the dotted line position, thereby disengaging or rendering idle the clutch 14, and the 105 movement of the actuators to the left will shift the fork 26 into the dotted line position, thereby throwing the clutch 15 into operation, thus causing a reversing of the direction of rotation of the shaft 8. If when 110 the forks are in the dotted line position Fig. 8 or the full line position Fig. 9, and the bolts 33 and 34 are thrown out in the opposite direction, or as shown in said Fig. 9, and the actuators are reciprocated, it will 115 be seen that the forks will be shifted into the dotted line position Fig. 9 or the full line position Fig. 8, thus again reversing the direction of rotation of the shaft 8. In this embodiment of my invention, the two actuators 31 and 32 are operated separately, although while preferable this is not essential. The actuator 32 has at one end a slot in which is received a crank-pin 35 on a crank-shaft 36 which is suitably journaled 120 in the frame. Said shaft 36 has thereon a worm-gear 37 that meshes with and is driven by a worm 38 fast on the driving shaft 3. The actuator 32, therefore, is operated directly from the driving shaft 3. The ac- 125 130

tuator 31, on the other hand, is operated from the driven member 5, and for this purpose, I have shown said actuator as having rising therefrom at one end an arm 5 having a roll 40 adapted to be engaged by a cam 41 carried by the driven member 5. The cam 41 by engaging the roll 40 moves the actuator 31 to the right, Fig. 1, and said actuator is returned to its normal position 10 by suitable springs 42, see Figs. 2 and 16.

The actuator 32 is that which throws the clutches into operation when the bolts are properly adjusted, and the actuator 31 is that which throws the clutches out of operation. It will be seen, therefore, that the actuator which throws the clutches into operation derives its movement directly from the driving member, while the actuator which throws the clutches out of operation 20 derives its movement from the driven member.

The bolts 33 and 34 are controlled as to their position by a suitable controlling device which I will now proceed to describe.

Referring to Figs. 1, 7, 10, 11, 20 and 21, it will be seen that the bolts 33 and 34 are slidably mounted in transverse grooves in the actuators 31 and 32, respectively. Each bolt has a transverse groove in its upper face, the grooves in the two bolts being designated 43, and 44, respectively.

45 and 46 designate projections, the lower ends of which are received in the grooves 43 and 44, respectively, and which depend from 35 two slides 47 and 48 that are slidably mounted in a cap or bridge-piece 49. Said projections extend through slots 50 and 51 in the actuator 31, said slots permitting the actuator to be reciprocated without interfering with the movement of the slides. The connection between the projections 45 and 46 and the bolts is such as to permit the bolts to move with the actuators without withdrawing the projections from the 45 grooves 43 and 44.

52 designates a T-shaped lever pivoted to the bridge-piece and having two arms 53 and 54 which engage the slides 47 and 48. The third arm of said lever is connected by 50 a link 55 with an arm 56 secured to an oscillating shaft 57 (see Fig. 22). This shaft 57 is adapted to be oscillated in either direction, thereby to turn the T-lever 52 in either direction from its central position 55 shown in Fig. 16. In the position shown in Fig. 16, the bolts 33 and 34 are in their normal position, both standing within the limits of the actuator, but by swinging the T-lever in one direction or the other, the 60 bolts may be thrown either into the position shown in Fig. 8 or into that shown in Fig. 9.

The connection between the arms 53 and 54 of the T-lever 52 and the slides 47 and 48 is preferably a yielding connection for

reasons which will be more fully herein-after explained. To obtain this yielding connection, I have shown the ends of each of the arms 53 and 54 as confined between two yielding members, shown as pins 58, 70 see Fig. 16, each of said members being backed by a suitable spring 59. The springs 59 are of such a strength that under ordinary conditions, the turning of the lever 52 will not compress them but will instead 75 move the slides 47 and 48, thereby to shift the bolts 33 and 34. If, however, either bolt should meet an obstruction, the corresponding spring will yield and thus permit the lever 52 to be thrown without breaking 80 any of the parts.

The means I have herein illustrated for governing the operation of the controller and thereby governing the times at which the reversing action will take place is in 85 the nature of a time mechanism which can be adjusted to cause a reversal to take place at any predetermined time, that is, after the driven member 5 has made any predetermined number of revolutions. The time 90 mechanism herein illustrated will now be described.

Fast on the shaft 57 are two arms 60 and 61 which are adapted to be actuated alternately by a suitable cam member 62 slidably 95 mounted on a shaft 63. This cam member has a long screw-threaded hub 64 (see Fig. 17) which is screw-threaded through a fixed nut 65, and said hub has splined thereto a gear-wheel 66 that meshes with and is 100 driven by a gear 67 fixed to the driven member 5. From this construction it will be seen that the rotation of the gear 66 will result in screwing the hub 64 through the nut 65 and thus both rotating the cam member 62 and advancing it along the shaft 63. This cam member 62 has on each face a spiral cam shoulder 68 which is so arranged that as the cam is rotated and advanced to the left Fig. 17, for instance, the cam 110 surface 68 on the left hand side of said disk will engage the end of the lever 61 and thereby rock the shaft 57 into the dotted line position Fig. 23, thus causing the T-lever 52 to be turned into position to project the bolts 33 and 34 into the position 115 shown in Fig. 9, whereby a reversal of the direction of rotation of the driven member will take place as above described. This reversal of the direction of rotation of the 120 driven member obviously causes a reversal in the direction of rotation of the cam 62 and its connected hub 64, and said cam 62 then moves to the right Fig. 17 until the cam-shoulder 68 on the right-hand side of 125 the disk 62 engages the lever 60 when said lever 60 will be thrown into the full line positions Fig. 23, thereby causing the T-lever 52 to be swung into the position shown in Fig. 7, and the bolts into the position 130

shown in Fig. 8. This will result in shifting the clutches to again reverse the direction of rotation of the driven member 5.

In the present embodiment of my invention, the gear 67 is a mutilated gear, so that the hub 64 is rotated intermittently and during a portion only of the rotation of the driven member 5. The length of the gear 67 however is such that the gear 66 is rotated once during each rotation of the gear 67. I employ this construction so that the movement of the cam disk 62 when it moves will be comparatively rapid, thus causing a quick reversal of the clutches.

After the shaft 57 has been turned in either direction, thereby to operate the lever 52, the parts are immediately restored to their normal or neutral position, as shown in Fig. 1, by the movement of the actuator 31. For this purpose, the projection 46 has thereon a fin 680, and the slot 51 is provided with a narrow extension 69 which is connected with the wider portion thereof by inclined surfaces 72 (see Fig. 16). With this construction, it will be seen that the movement of the actuator 31 to the left, Figs. 1 and 16, will center the slide 48 by the engagement of one of the inclined surfaces 72 with the fin 680, thus withdrawing the bolt 34 and throwing the T-lever 52 into its central position, as shown in Fig. 16, this operation also resulting in withdrawing the bolt 33.

The normal position of the actuator 31 is to the left with the fin 680 occupying the groove 69, and therefore the slide 48 and its projection 46 are normally locked against movement by said fin 680, and said slide is released only when the actuator 31 is moved forwardly or into the position shown in Figs. 1 and 16 by the cam 41, and this occurs only when the driven member 5 is in a predetermined position. I have adopted this construction so as to insure the reversal of the mechanism only when the driven member 5 is in a predetermined position.

If the shaft 57 is operated in either direction while the slide 31 is in its normal position to the left, the lever 52 will be turned and the slide 47 moved to project the knock-out bolt 33 outwardly. The knock-in bolt 34, however, is not projected as the slide 48 is locked, and therefore the reversing operation does not take place until the slide 31 is thrown into the position shown in Figs. 1 and 16 by the cam 41 which occurs when the driven member is in its predetermined position. The movement of the actuator 31 to the right, as shown in Fig. 1, brings the projected end of the knock-out bolt 33 into engagement with the nose of the corresponding fork and releases the clutch which is active or in operation, and as soon as the actuator 31 has been moved sufficiently to release the fin 680, the slide 48 is operated, by its springs 59, thereby to project the knock-

in bolt 34, and the latter is brought against the other fork by the reciprocating of the actuator 32, thereby throwing the other clutch into operation. It will thus be seen that the reversal can only be done when the driven member 5 is in a predetermined position.

In order to make the timing mechanism capable of reversing at different stated periods of time, I have adjustably mounted the arm 61 on the shaft 57 so that said arm may be placed at different distances from the arm 60. For this purpose, the arm 61 is shown as having a hub 70 which is slidably mounted on the shaft 57, but which may be locked in position on the shaft by means of a pin 71 which is adapted to enter any one of a number of holes 720 in the shaft, see Fig. 17. The hub 64 is provided with two spaces 73 having no screw-threads, and the shaft 63 has thereon at each end a cushion or spring 74. This construction is adopted so that when the hub 64 has been advanced to its maximum distance either to the left or to the right, Fig. 17, one of the smooth portions 73 thereof will come opposite the screw-threads in the nut 65, and either the disk 62 or the end of the hub 64 will engage and compress one of the springs 74. When the parts have reached either one of these positions, the hub will not be advanced any further, even though the rotation thereof continues.

The springs 74 are for the purpose of throwing the screw-threads on the hub and the nut into engagement immediately upon the reversal of the direction of rotation if, just previous to reversal, the hub has been screwed entirely out of the nut in either direction. In addition to these features, I have provided a manually-controlled device for stopping the driven element or for causing it to continue its rotation indefinitely without reversal in either direction.

Referring now to Figs. 7, 10 and 11, it will be seen that the slides 47 and 48 have formed on their upper sides transverse grooves 75 and 76, respectively. Situated above the slides and movably mounted in the bridge or head 49 is a starting-and-stopping slide 77 from which depends pins 78, 79 and 80. The slide 77 has connected thereto a rod 81 which is connected to a manually-controllable lever 82 by which said slide is operated.

When the starting-and-stopping slide is in its normal position, as shown in Fig. 11, the slides 47 and 48 can be moved freely. When the slide 77 is moved to the right into the full line position Fig. 10, the pin 79 enters the groove 76 in the slide 48, and thus locks said slide from movement and holds it in its central position, and the pin 78 passes clear through the groove 75 in the slide 47 and therefore does not interfere with the

free movement of the said slide 47. When the said starting-and-stopping slide is moved into the central position shown in dotted lines Fig. 10, the pin 78 enters the groove 75 in the slide 47, and the pin 80 enters the groove 76 in the slide 48. When the parts are in this position, both of the slides 47 and 48 are locked from movement in either direction.

10 When it is desired that the mechanism should run normally, and reverse itself at stated intervals of time, the starting-and-stopping slide 77 is moved into the position shown in Fig. 11, thereby to release the 15 slides 47 and 48, so that they can have free movement in either direction.

When it is desired that the machine should run continuously in one direction without reversing, the starting-and-stopping slide is 20 moved into the dotted line position, Fig. 10, thereby to lock both the slides 47 and 48, for when these slides are thus locked, neither clutch can be operated, and as a result the mechanism will run without reversing.

25 When it is desired to stop the mechanism, the starting-and-stopping slide 77 is moved into the right-hand position, as shown in full lines Fig. 10, in which position the slide 48 is locked, while the slide 47 is free for 30 movement to disengage or release the clutch which is in operation.

The lever 82 for operating the starting-and-stopping slide works in connection with a quadrant 83, provided with notches adapted to hold the lever in any one of its three 35 positions.

It is often desirable to bring the mechanism with which this reversing mechanism may be used to rest instantly, whenever both 40 clutches are disengaged, and to accomplish this I have provided a brake mechanism which is normally inactive, but which is rendered active to instantly stop the mechanism whenever both clutches are released.

45 The brake mechanism herein shown comprises a brake-band 84, which is located within a hub or flange 85 formed on the gear 13. It will be remembered that said gear 13 is fast to the shaft 8. The brake is set by 50 expanding the brake band outwardly against the flange 85, such expanding operating to apply sufficient friction to the flange to bring the shaft 8 to rest and hold it in such position. The two ends of the brake-band 84 are connected to two independently-movable sliding members 86, 87 (shown in dotted lines Fig. 5), and each of said sliding members has a socket or recess in which is received one of two projections 88 carried by a brake actuator 89. This latter has connected thereto a rod 90 which in turn is connected to an arm of a rock-shaft 91. This rock-shaft 91 has fast thereto an arm 92 to which is connected a member 93 that leads to the lever 82.

65 The connection between the lever 82 and

the arm 92 is a yielding connection, so that said lever may be operated without causing the brake to be applied until both clutches are released. For this purpose, the member 93 is made in two sections which telescope 70 together, and are yieldingly maintained in their proper relative positions by means of a spring 94. The member 93 also has a pin-and-slot connection with lever 82, said lever for this purpose having an arm 95 extending 75 therefrom provided with a pin 96 that enters a slot 97 in the end of member 93.

It is necessary that the brake should not be applied except when both clutches are released, and I have therefore provided a lock 80 for normally holding the brake inoperative, which lock is released automatically to permit the brake to be applied only when both clutches are released.

Referring now to Figs. 15 and 16, it will 85 be seen that the rock-shaft 91 has fast thereto an arm 98 provided with a locking notch that is normally engaged by a locking latch 99, that is suitably pivoted as at 100. This locking latch has rigid therewith an arm 190 90 (the end of which is shown in Fig. 18) which has a cam projection 101, which is adapted to coöperate with a cam projection 102 on the end of a slide 103 (one end of which is shown in Fig. 19), which is mounted in a 95 groove in the actuator 31, and is adapted to move transversely thereof (see Fig. 1). This slide 103 has on its upper face a groove 104 in which is received a fin 105 on the underside of a sliding member 106 that is 100 mounted to slide transversely in the bridge or cover 49.

The sliding member 106 has at one end a V-shaped groove 107 in which is received a projection 108 (see Fig. 22) formed either 105 on the end of lever 56, or on the end of the link 55.

When the parts are in their normal position, as shown in Figs. 1 and 22, the projection 108 stands at the apex of the groove 107, 110 and the sliding member 106 and consequently the slide 103 are in their withdrawn position in which position the cam projection 102 is out of line with the cam projection 101 on the locking latch, so that the reciprocating movement of the slide 103, due to the movement of the actuator 31 does not release the locking latch 99. When, however, the shaft 57 is turned in either direction by the cam 62, thereby to set the clutch-releasing and clutch-engaging mechanism, the sliding member 106 is carried forwardly, thereby throwing the projection 102 into line with the cam projection 101, and when the parts have assumed this position the movement of the actuator 31 to cause the release of either clutch, lifts the locking pawl 99 out of engagement with the arm 98.

The rock-shaft 91 has fast thereto a weighted arm 167, which, if unrestrained, 130

would tend to set the brake. The length of the connection 93 is such that when the lever 82 is in its central position, as shown in Fig. 1, which is the position of the lever when the machine is running continuously in one direction, the spring 94 will be under sufficient tension to counterbalance the weighted arm 167 so that even if the lock 99 is released the brake will not be applied.

10 When the lever 82 is thrown into its right hand position, Fig. 1, which is the position occupied by it when the machine is running normally and reversing at stated periods, the spring 94 is placed under still greater tension, as will be obvious, and in this condition it more than counterbalances the weighted arm 167. So long therefore as the lever 82 is in either the central or right hand position, Fig. 1, the brake cannot be applied even though the locking latch 99 is released. When, however, the lever 82 is thrown to the left hand position, Fig. 1, which is the position when it is desired to stop the machine, the tension on the spring 94 will be relieved and the pin 96 will move down to the right hand end of the slot 97. The latch 99 is then the element which holds the brake from being applied. When the parts have assumed this position the machine will run until the clutch is released and the slide 103 projected outwardly thereby to release the locking latch 99 by the reciprocating movement of the actuator 31. When this occurs the weighted arm 167 comes into play to apply the brake and stop the parts instantly.

In order to prevent the brake from being set before the clutch is released when it is desired to stop the machine, it is desirable 40 to provide means for preventing the stopping-and-starting slide 77 from being thrown to the right or into the full line position Fig. 10, except when the slide 31 is in its normal position to the left with the roll 40 against the low portion of the cam 41. To accomplish this object, I have provided 45 a lock 200 which is slidably mounted in the bridge piece 49, and is provided at its lower end with a cam surface 201. This lock is 50 yieldingly held against the slide 31 by means of a spring 202 (see Fig. 1) and is provided in one side with a notch 203 (see Figs. 12 and 13). The end of the stopping-and-starting slide 77 is provided with a rib 204 55 adapted to pass through the notch 203 when the lock 200 is properly positioned.

When the lock is in the position shown in Fig. 1, which is that shown in dotted line position Fig. 13, the notch 203 is out of line 60 with the rib 204 and it will be impossible, therefore, when the parts are in this position to move the stopping-and-starting slide 77 to the right or into the full line position Fig. 10. When, however, the cam 41 is 65 turned so as to permit the slide 31 to be

moved into its normal position to the left, the cam surface 205 upon the slide engages the cam surface 201 on the lock and raises the latter to bring the notch 203 therein opposite the rib 204 on the stopping-and-starting slide 77 so that when the slide 31 is in its position to the left Fig. 1, the slide 77 is free to be moved to the right to stop the machine.

I have provided a frictional connection between the cam 41 and the gear 5 so as to get what amounts to a longer dwell on said cam. As shown in Figs. 1, 2 and 14, the shaft 6 has fast thereto a plate member 206 provided with a nose 207. This plate member is provided with a hub 208 on which the cam 41 is loosely mounted, and the cam bears against friction blocks 109 carried in the driven member 5.

110 represents a spring plate retained in position by a screw 111 and adapted to bear against friction blocks 112 that are received in apertures in the plate 206 and bear against the outer face of the cam member 41. Said cam member is provided with two stops 90 or projections 113 against one of which the nose 207 is adapted to abut, as shown in Fig. 1. The parts are shown in Fig. 1 in the position they occupy when the cam is moving in the direction of the arrow s. The reversing 95 of the mechanism will always take place when the roll 40 is bearing against the low portion of the cam 41, that is, when the slide 31 is in its position to the left Fig. 1, and when the reverse takes place the cam 41 will 100 remain stationary until the plate 206 which is fast with the shaft turns sufficiently to bring the nose 207 against the projection 113 when the movement of the cam 41 is taken up and it then rotates uniformly with 105 the driven member.

I have also shown thrust-collars 120 against which the ends of the worm 7 are adapted to bear, said collars being preferably provided with anti-friction bearings. 110 These thrust-collars are for the purpose of taking the end-thrust in the shaft 8. 121 is a hand wheel secured to the shaft 8 by which the parts may be adjusted or turned if desired.

I have not attempted herein to show all embodiments of my invention which may be covered by the appended claims, but for the purpose of illustrating the invention I have selected one embodiment only thereof.

Having fully described my invention, what I claim as new and desire to secure by Letters Patent is:—

1. In a reversing mechanism, a rotary driving member, a rotary driven member, 125 said driving and driven members rotating about different axes, reversing mechanism between said members, said reversing mechanism including non-axially-aligned friction clutches, a controller for the reversing mech- 130

anism and automatic means for operating the controller.

2. In a reversing mechanism, a rotary driving member, a rotary driven member, 5 said driving and driven members rotating about different axes, reversing mechanism between said members, said reversing mechanism including non-axially alined friction clutches, a controller for the reversing mechanism, and an adjustable time mechanism 10 governing the time of operation of the controller.

3. In a device of the class described, a driving member, a driven member actuated 15 thereby, and reversing means between said members to reverse the direction of movement of the driven member, said reversing means being actuated partly by the driving member and partly by the driven member.

20 4. In a device of the class described, a driving member, a driven member actuated thereby, reversing means between said members to reverse the direction of movement of the driven member, said reversing means being actuated partly by the driving member and partly by the driven member, and a controller controlling the time of operation 25 of said reversing mechanism.

5. In a device of the class described, a 30 driving member, a driven member actuated thereby, reversing means between said members to reverse the direction of movement of the driven member, said reversing means being actuated partly by the driving member and partly by the driven member, and a time-governed controller controlling the 35 time of operation of said reversing mechanism.

6. In a device of the class described, a 40 driving shaft, a separate driven shaft, reversing gearing connecting said shafts, said reversing gearing including two clutches, one on each shaft and means to throw said clutches, and a controller to govern the time 45 of operation of the reversing mechanism.

7. In a device of the class described, a 50 driving shaft, a separate driven shaft, reversing gearing connecting said shafts, said reversing gearing including two clutches one on each shaft and means to throw said clutches, and a time mechanism to govern the operation of the reversing mechanism.

8. In a device of the class described, a 55 driving shaft, a separate driven shaft, reversing gearing connecting said shafts, said reversing gearing including a clutch on each shaft and means to throw said clutches, and an adjustable time mechanism to govern the operation of the reversing mechanism, 60 whereby the reversing may take place at different predetermined intervals of time.

9. In a device of the class described, a 65 driving member, a driven member, reversing gearing connecting said members, said reversing gearing including two clutches,

means actuated by one member to throw the clutches into operation, and by the other member to throw the clutches out of operation.

10. In a device of the class described, a 70 driving member, a driven member, reversing gearing connecting said members, said reversing gearing including two clutches, and means actuated by the driving member to throw the clutches into operation and by 75 the driven member to throw the clutches out of operation.

11. In a device of the class described, a driving member, a driven member, reversing gearing connecting said members, said 80 reversing gearing including two clutches, means actuated by one member to throw the clutches into operation and by the other member to throw the clutches out of operation, and time mechanism to govern the 85 times of operation of the reversing mechanism.

12. In a device of the class described, a driving member, a driven member, reversing gearing connecting said members, said 90 reversing gearing including two clutches, means actuated by one member to throw the clutches into operation and by the other member to throw the clutches out of operation, and an adjustable time mechanism to 95 govern the times of operation of the reversing mechanism.

13. In a device of the class described, a driving member, a driven member, reversing gearing connecting said members, said 100 reversing gearing including two clutches, means actuated by the driving member to throw the clutches into operation and by the driven member to throw the clutches out of operation, and an adjustable time mechanism to govern the times of operation of the 105 reversing mechanism.

14. In a device of the class described, a driving shaft, a driven shaft, a sprocket-wheel fast on one shaft, a gear loose thereon, 110 a second sprocket-wheel loose on the other shaft, and a second gear fast thereon, a chain connecting said sprocket-wheels, and a clutch on each shaft for clutching the sprocket-wheel thereon to the gear thereon. 115

15. In a device of the class described, a driving shaft, a driven shaft, a sprocket-wheel fast on one shaft, a gear loose thereon, a second sprocket-wheel loose on the other shaft, a second gear fast thereon, a chain 120 connecting said sprocket-wheels, a clutch on each shaft for clutching the sprocket-wheel thereon to the gear thereon, and means operated by one shaft to throw the clutches out of operation and by the other shaft to throw 125 them into operation.

16. In a device of the class described, a driving member, a driven member, reversing mechanism between said members, said reversing mechanism including two clutches, 130

- an actuator operated by the driving member to throw the clutches into operation, and another actuator operated by the driven member to throw them out of operation.
- 5 17. In a device of the class described, a driving member, a driven member, reversing gearing connecting said members, said reversing gearing comprising two clutches, means operated by the driven member to 10 unclutch the active clutch, and means operated by the driving member to simultaneously clutch the inactive clutch.
- 15 18. In a device of the class described, a driving member, a driven member, reversing gearing connecting said members, said reversing gearing comprising two clutches, an actuator operated by the driving member for throwing the clutches into operation, another actuator operated by the driven member for 20 throwing the clutches out of operation, a bolt carried by each actuator, and means to throw the bolts into and out of operative position.
- 25 19. In a device of the class described, a driving member, a driven member, reversing gearing connecting said members, said reversing gearing comprising two clutches, an actuator operated by the driving member for throwing the clutches into operation, another actuator operated by the driven member for throwing the clutches out of operation, a bolt carried by each actuator, and a time mechanism for throwing the bolts into and out of operative position.
- 30 20. Driving and reversing mechanism comprising a driving member, a driven member, gears on and connecting said members clutches and clutch engaging members therefor to lock said gears to the driving and driven members, a clutch unlocking actuator operated from the driven member, a clutch locking actuator substantially vertically positioned relative to the unlocking actuator and operated from the driving member, members on each of said actuators adapted for both lateral and longitudinal movement and actuated from the driven member to actuate the clutch engaging members.
- 35 21. In a device of the class described, a driving member, a driven member, reversing means between said members actuated partly by the driving member and partly by the driven member, and an automatically operative brake for the driven member.
- 40 22. In a device of the class described, a driving member, a driven member, reversing gearing connecting said members, said reversing gearing including two clutches, means to throw said clutches, a controller to govern the time of operation of the reversing mechanism, a brake for the driven member, and automatic brake controlling mechanism.
- 45 23. In a device of the class described, a driving member, a driven member, reversing gearing connecting said members, said reversing gearing including two clutches, means to throw said clutches, a controller to govern the time of operation of the reversing mechanism, a brake for the driven member, and automatic means to set the brake when both clutches are disengaged.
- 50 24. In a device of the class described, a driving member, a driven member, reversing gearing connecting said members, said reversing gearing including two clutches, means to throw said clutches, a controller to govern the time of operation of the reversing mechanism, a brake for the driven member, and automatic means to hold the brake inoperative so long as either clutch is in operation, and automatic means to apply the brake when both clutches are inoperative.
- 55 25. In a device of the class described, a driving member, a driven member, reversing gearing connecting said members, said reversing gearing including two clutches, means actuated by the driving member to throw the clutches into operation and by the driven member to throw the clutches out of operation, a brake for the driven member, and automatic means to apply the brake when both clutches are inoperative.
- 60 26. In a device of the class described, a driving member, a driven member, reversing gearing connecting said members, said reversing gearing including two clutches, and means actuated by the driving member to throw the clutches into operation and by the driven member to throw the clutches out of operation, a brake for the driven member, means normally holding said brake inoperative, and means to apply the brake when both clutches are thrown out of operation.
- 65 27. In a device of the class described, a driving member, a driven member, reversing mechanism between said members, said reversing mechanism including two clutches, an actuator operated by the driving member to throw the clutches into operation, another actuator operated by the driven member to throw them out of operation, a brake for the driven member, means to normally hold the brake inoperative, and mechanism controlled by one of the actuators to render said means inoperative.
- 70 28. In a device of the class described, a driving member, a driven member, reversing mechanism between said members, said reversing mechanism including two clutches, an actuator operated by the driving member to throw the clutches into operation, another actuator operated by the driven member to throw them out of operation, an automatically operated brake for the driven member and a lock to hold the brake inoperative, and means operated by one of the actuators to release the lock.
- 75 29. In a device of the class described, a

- driving member, a driven member, reversing gearing connecting said members, said reversing gearing comprising two clutches, an actuator operated by the driving member for 5 throwing the clutches into operation, another actuator operated by the driven member for throwing the clutches out of operation, a bolt carried by each actuator, and means to throw the bolts into and out of operative 10 position, an automatically operative brake for the driven member, a lock to hold said brake normally inoperative, and means operated by the latter actuator for releasing said lock.
- 15 30. A reversing mechanism comprising in combination driving instrumentalities, driven instrumentalities, means to lock together portions of said driving and driven instrumentalities comprising a frictional 20 clutch, means to lock together other portions of said driving and driven instrumentalities comprising another frictional clutch, clutch actuating means operated by the driven and driving members to effect alternate periodic 25 engagement of said clutches, adjustable timing means to determine the periods of operation of said clutch actuating means and yielding means to transmit the action of said timing means to said clutch actuating means.
- 30 31. In a device of the class described, a driving member, a driven member, gears on and connecting said members, clutches for locking the gears to said members, clutch engaging members, a clutch actuator therefor operated from the driving member, a clutch actuator operated from the driven member, a movable member connected with each of said actuators and adapted to be 35 positioned to actuate a clutch engaging member.
- 40 32. In a reversing mechanism, the combination with a continuously-rotating driving member, of a driven member, reversing mechanism between said members for driving the driven member in either direction from the driving member, automatic means for operating the reversing mechanism, and a manually-operated device separate from said automatic means and adapted in one 45 position to render the reversing mechanism inoperative to reverse the direction of the driven member whereby the latter will be rotated continuously in one direction and in another position to disconnect the driven member from the driving member whereby the driven member will be stopped.
- 50 55 33. In a reversing mechanism, the combination with a continuously-rotating driving member, of a driven member, reversing mechanism between said members for driving the driven member in either direction from the driving member, automatic means for operating the reversing mechanism, a manually-operated device separate from said 60 automatic means and adapted in one position to render the reversing mechanism inoperative to reverse the direction of the driven member whereby the latter will be rotated continuously in one direction and in another position to disconnect the driven member from the driving member whereby the driven member will be stopped.
- 65 34. In a reversing mechanism, the combination with a continuously rotating driving member, of a driven member, reversing mechanism between said members for driving the driven member in either direction from the driving member, automatic means for operating the reversing mechanism, a manually-operated device separate from said automatic means and adapted in one position to render the reversing mechanism inoperative to reverse the direction of the driven member whereby the latter will be stopped, a brake for the driven member, means to hold the brake inoperative while the reversing mechanism is operative, and automatic means to release the brake and permit it to be applied when the driven member is disconnected from the driving member.
- 70 75 35. In a reversing mechanism, the combination with a continuously-rotating driving member, of a driven member, reversing mechanism between said members for driving the driven member in either direction from the driving member, automatic means for operating the reversing mechanism, a manually-operated device separate from said automatic means and adapted in one position to render the reversing mechanism inoperative to reverse the direction of the driven member whereby the latter will be stopped, a brake for the driven member, and means controlled by said manually-operated device to render the brake operative when the driven member is disconnected from the driving member.
- 80 85 36. In a device of the class described, a driving member, a driven member, gears on and connecting said members, clutches for locking the gears to said members, clutch engaging members, a clutch actuator therefor operated from the driving member to lock the clutches, a clutch actuator operated from the driven member to unlock the

clutches, a movable bolt connected with each actuator and adapted to be positioned to engage a clutch engaging member.

37. In reversing mechanism, clutch shifting mechanism comprising in combination, clutch engaging members, clutch actuators therefor movable bolts connected with the actuators and adapted to be positioned to actuate said engaging members, bolt actuating and controlling means comprising slides capable of lateral motion relative to said bolts, a lever having yielding connection with said slides, and timing means for regulating the time of operation of said actuating and controlling means.

38. In reversing mechanism, clutch shifting mechanism comprising in combination, clutch engaging members, clutch actuators therefor movable bolts connected with the actuators and adapted to be positioned to actuate said engaging members, bolt actuating and controlling means comprising slides capable of lateral motion relative to said bolts, a lever having yielding connection with said slides, and timing means for regulating the time of operation of said actuating and controlling means comprising a shaft, a yoke thereon, a cam for actuating

the yoke arms alternately, and means operated from the driven member for actuating said cam.

39. In reversing mechanism, clutch shifting mechanism comprising in combination, clutch engaging members, clutch actuators therefor movable bolts connected with the actuators and adapted to be positioned to actuate said engaging members, bolt actuating and controlling means comprising slides capable of lateral motion relative to said bolts, a lever having yielding connection with said slides, and timing means for regulating the time of operation of said actuating and controlling means comprising a shaft, arms thereon, a cam with an extended hub having threaded connection with a bearing, means operatively connecting said hub with the driven member to rotate said cam and its shaft to cause it alternately to engage said arms to actuate said bolts.

In testimony whereof, I have signed my name to this specification in the presence of two subscribing witnesses.

WILLIAM A. E. HENRICI.
